UNITED STATES PATENT OFFICE.

DANIEL R. SCHOLES, OF CHICAGO, ILLINOIS, ASSIGNOR TO THE AERMOTOR COMPANY, OF CHICAGO, ILLINOIS, A CORPORATION OF ILLINOIS.

SIDEREAL SPHERE.

1,099,315.

Specification of Letters Patent. Patented June 9, 1914.

Application filed June 27, 1913. Serial No. 776,052.

To all whom it may concern:

Be it known that I, DANIEL R. SCHOLES, a citizen of the United States, residing at Chicago, in the county of Cook and State of Illinois, have invented a certain new and useful Improvement in Sidereal Spheres, of which the following is a full, clear, concise, and exact description, reference being had to the accompanying drawings, forming a part 10 of this specification.

In the sidereal sphere of the United States Patent No. 1,019,405 to W. W. Atwood, dated March 5, 1912, an observers' platform was employed, necessitating complete entry 15 of observers within the sphere in order to view the simulated heavens, this construction being expensive and, moreover, ill adapted to spheres of smaller diameters.

By means of my invention an observer 20 may stand within the sphere upon the same general level upon which the structure is supported, whereby the platform within the sphere may be dispensed with.

In the preferred construction the sphere, 25 which has an axis of rotation inclined with respect to the horizontal, is formed of thin material and has a band or ring engaging the sphere in its equatorial plane, there being a mounting upon which the ring is rotatably supported. The sphere is preferably 30 made of sheet galvanized steel one sixtieth of an inch thick. This sphere is preferably provided with sufficiently minute perforations to enable light to shine through 35 from the exterior to represent stars. The employment of said rotatably supported ring and the small perforations is not new with me.

The lower polar zone is removed to permit 40 of entry within the sphere. Where star simulating perforations are formed in the sphere, the opening that is afforded by the removal of the lower polar zone is provided with a light excluding closure. A stationary 45 horizon ring is disposed close to and within the sphere on a horizontal plane that includes the center of the sphere. Another stationary ring margins the entrance to the sphere. These two rings are connected by 50 a view obstructing screen to limit the observation of the spectators within the sphere to the stellar representations appearing above the horizon ring.

I will explain my invention more fully by 55 reference to the accompanying drawing

showing the preferred embodiment thereof and in which—

Figure 1 is a view in sectional elevation; Fig. 2 is an external perspective view; Fig. 3 shows a detail of construction employed at 60 the entrance to the sphere; and Fig. 4 is a sectional view illustrating the star representing perforations in the sphere shell.

Like parts are indicated by similar characters of reference throughout the different 65 figures.

The inclined axis of rotation of the sphere *a* is represented by the line *b*. The sphere, which is desirably of very thin sheet metal, preferably has a number of star representing 70 perforations *c* formed therethrough so that light may shine into the sphere interior from the sphere exterior to simulate stars. A supporting ring *d* surrounds the sphere in its equatorial plane and there engages it. A 75 standard *e* rotatably supports three pulleys *f* which are spaced one hundred and twenty degrees apart, these pulleys rotatably supporting the ring *d* in its inclined position, whereby the sphere may be turned upon its 80 axis indicated at *b*. The opening formed at the lower end of the sphere *a* by the removal of the bottom zone is provided with a bordering ring *g* rotating with the sphere. A stationary ring *h* margins the entrance opening, is formed preferably of angle iron and so positioned as to obstruct the passage of light between the rings *g* and *h*, and is secured at one place directly to the horizon ring *i*, distance preserving pieces *k* intervening at other places between these two rings. The bottom portion of the stationary 85 ring *h* is secured to the middle of the strut *l* which is attached at its ends to the horizontal stretches of the support *e* which, together 90 with the strut *l*, rest directly upon the floor *m* or other substantially horizontal level support (that is a support that lies in the same horizontal plane) that supports the sphere.

A light excluding closure is provided for 95 the entrance opening to the sphere, this closure being preferably formed of heavy cloth fabric hung before the entrance in the form of two curtains, depending from ring *h*, *n* between which an observer may readily 100 pass. The entrance opening is unobstructed, except for these light excluding curtains, so that the observer, while walking upon the floor *m* which supports the sphere, may readily enter without ascending, the for- 110

wardly inclined entrance opening directly overlying the floor *m* so as to permit of this.

The screen *o* prevents the simulation of stars which are below the horizon ring to the observer within the sphere and is preferably located within the sphere for this purpose. It surrounds the observer, being open at the bottom for the observer's entrance and at the top to permit the space within the sphere above the horizon ring freely to be seen. The screen is attached at its upper circular border to the horizon ring and at its lower circular border to the stationary ring *h*. Thus there are two distinct portions of the passage entered by the observer, one the vestibule formed by the curtains *n*, and the other the light intercepting screen *o* terminating at its upper end at the horizon ring *i* and at its lower end at the entrance opening 20 to the sphere.

While I have herein shown and particularly described the preferred embodiment of my invention I do not wish to be limited to the precise details of construction shown as 25 changes may readily be made without departing from the spirit of my invention, but

Having thus described my invention I claim as new and desire to secure by Letters Patent the following:—

30 1. A hollow sidereal sphere having a mounting upon which it is rotatably supported and defining an axis of rotation for the sphere which is inclined with respect to the horizontal, the sphere presenting stellar representations to view within its interior and having a bottom zone removed to form a forwardly inclined entrance opening thereto; and a support for the sphere which underlies the same and the inclined entrance 35 opening thereto, the portions of this support that underlie the sphere and the inclined entrance opening to the sphere being disposed substantially in one horizontal plane whereby the observer may view the stellar representations while upon a level within the sphere that is in the same general plane as the support for the sphere therein.

2. A hollow sidereal sphere having a mounting upon which it is rotatably supported and defining an axis of rotation for the sphere which is inclined with respect to the horizontal, the sphere presenting stellar representations to view within its interior and having a bottom zone removed to form a forwardly inclined entrance opening thereto; a screen for obliterating stellar representations below a horizontal line; and a support for the sphere which underlies the same and the inclined entrance opening 55 thereto, the portions of this support that underlie the sphere and the inclined entrance opening to the sphere being disposed substantially in one horizontal plane whereby the observer may view the stellar representations while upon a level within the sphere

that is in the same general plane as the support for the sphere therein, said screen permitting such entry.

3. A hollow sidereal sphere having a mounting upon which it is rotatably supported and defining an axis of rotation for the sphere which is inclined with respect to the horizontal, the sphere presenting stellar representations to view within its interior and having a bottom zone removed to 70 form a forwardly inclined entrance opening thereto; a horizon ring within the sphere; means for supporting the horizon ring, a view obstructing screen terminating at its upper end at the horizon ring and at its lower end at the sphere entrance thereby to 75 surround the observer, this screen being open at its bottom and top ends to permit the observer to enter and view the stellar representations and a support for the sphere 80 which underlies the same and the inclined entrance opening thereto, the portions of this support that underlie the sphere and the inclined entrance opening to the sphere being disposed substantially in one horizontal plane whereby the observer may view the stellar representations while upon a level 85 within the sphere that is in the same general plane as the support for the sphere.

4. A hollow sidereal sphere having a 90 mounting upon which it is rotatably supported and defining an axis of rotation for the sphere which is inclined with respect to the horizontal, the sphere having perforations therein to permit of the passage of light between the exterior and interior of the sphere, these perforations being sufficiently minute to represent stars, and having a bottom zone removed to form a forwardly inclined entrance opening thereto; a 95 stationary ring margining the entrance opening; a horizon ring within the sphere; a view obstructing screen terminating at its upper end at the horizon ring and at its lower end at the sphere entrance thereby to 100 surround the observer, this screen being open at its bottom and top ends to permit the observer to enter and view the stellar representations; and a light excluding closure 105 in the form of a curtain depending from the ring that margins the entrance opening.

5. A hollow sidereal sphere having a mounting upon which it is rotatably supported and defining an axis of rotation for the sphere which is inclined with respect to the horizontal, the sphere presenting stellar representations to view within its interior and having a bottom zone removed to form a forwardly inclined entrance opening 120 thereto; a stationary ring margining the entrance opening; a horizon ring within the sphere; a view obstructing screen terminating at its upper end at the horizon ring and at its lower end at the sphere entrance there. 125

by to surround the observer, this screen being open at its bottom and top ends to permit the observer to enter and view the stellar representations; a light excluding closure in the form of a curtain depending from the ring that margins the entrance opening; and a support for the sphere which underlies the same and the inclined entrance opening thereto, the portions of this support that underlie the sphere and the inclined entrance opening to the sphere being

disposed substantially in one horizontal plane whereby the observer may view the stellar representations while upon a level within the sphere that is in the same general plane as the support for the sphere. 15

In witness whereof, I hereunto subscribe my name this 25th day of June, A. D. 1913

DANIEL R. SCHOLE.
